Hardway & Cashy,
ATTORNEY'S

UNITED STATES PATENT OFFICE.

REDUS D. DODDS, OF HOUSTON, TEXAS.

CORE-TAKING DEVICE.

1,427,268.

Specification of Letters Patent. Patented Aug. 29, 1922.

Application filed September 18, 1920. Serial No. 411,059.

To all whom it may concern:

Be it known that I, REDUS D. DODDS, a citizen of the United States, residing at Houston, in the county of Harris and State 5 of Texas, have invented certain new and useful Improvement in Core-Taking Device, of which the following is a specification.

This invention relates to new and useful improvements in a core taking device.

10 One object of the invention is to provide a device of the character described adapted to take cores, or samples of the formation in drilling wells.

15 With the above and other objects in view the invention has particular relation to certain novel features of construction, operation and arrangement of parts, an example of which is given in this specification and illustrated in the accompanying drawings,

20 wherein:—

Figure 1 shows a vertical sectional view of the upper part of the device in position to be withdrawn from the stem.

25 Figure 2 shows a similar view of the lower part thereof, and

Figures 3 and 4 show sectional views of the device as anchored in the stem.

In the drawings, the numerals 1 and 2 show upper and lower sections of a tubular 30 stem, the former of which is screwed into the latter. The lower end of the section 2 has a connecting nipple 3 threaded into it, and to this nipple the core forming bit 4 is attached, having a central opening 5 to ad-

35 mit the core. This bit has the usual water passageways 6, 6 to conduct the water to the cutting blades of the bit, and the wall of the opening 5 has an annular groove 7 wherein the lower end of the tubular anchor 8 rests.

40 The walls of this anchor taper downwardly, forming a tapering seat for the core engaging dogs 9. These dogs have their inner faces transversely corrugated or toothed. Preferably four dogs are provided, and sur-

45 rounding them is an expandable band 10 to which they are attached. Each dog has a push rod 11 attached to its upper end, said rods working through outwardly inclined bearings in the anchor, and attached to the

50 upper end of each rod there is a flexible finger 12 whose upper free end presses against the tubular core barrel 13. The anchor is connected to the lower end of this barrel and the upper end of said barrel is 55 attached to the nut 14 which is threaded onto the lower end of the swivel 15. Surround-

ing this swivel is a tubular housing 16 between the lower end of which and said nut are the anti-friction bearings 17. The upper end of the housing 16 is screwed into the 60 lower end of the tubular anchor support 18, and the upper end of the swivel 15 is formed into an enlarged head 19 which has a swiveling connection with said support 18. Pivoted within said support are the blade- 65 like anchors 20, 20 which work through side slots 21, 21 therein and whose upper ends are formed with upwardly projecting fingers 22, 22. Within the upper end of the support 18 there is screwed a gland 23 through 70 which the stem 24 of the plunger 25 works. This plunger is of the form of an inverted cone, and surrounding its stem is a coil spring 26 which is interposed between the plunger and gland. 75

Threaded onto the reduced upper end of the gland 23 there is the tubular housing 27 having the side slots 28, 28, and in it there is a cylindrical block 29 having deep elongated recesses 30, 30 aligned with the slots 80 28 and in which the anchor blades 31, 31 are pivoted at their lower ends, said blades working through the slots 28. This block has a depending stem 32 which has a bearing in the gland 23, and surrounding this stem 85 32 and interposed between said gland and block there is a coil spring 33. The blades 31 have long outwardly diverging bearings 34, 34, through which the pins 35, 35, anchored in the housing 27, pass. 90

Threaded into the upper end of the housing 27 there is a tubular release head 36, conical shaped in general contour, and extending through it there is a stem 37, formed integrally with the block 30. The upper end 95 of the stem is formed with an annular shoulder 38 formed for the purpose of engaging with the dogs 39, 39 which are hinged to the lower end of the tubing 40, and held in engagement with said shoulder by means of a 100 pull spring 41 attached to said dogs.

The device is first assembled, as shown in Figures 1 and 2, and let down into the bore. With the bit 4 resting on the bottom of the bore the anchor 8 will seat in the groove 105 7 and the pressure of the spring 26 will force the plunger 25 between the fingers 22, forcing the anchor blades 20, 20 through the slots 21 and into engagement with the upper end of the connecting nipple 3. 110 Meanwhile the upper ends of the anchor blades 31 have passed below the lower end

of the section 1 and thereupon the spring 33 forces the block 29 and the blades 31 upwardly, and the bearings thereof riding on the pins 35 carry the upper ends of said blades outwardly into engagement with said end of said section 1. The core taking mechanism is thus anchored relative to the stem and bit. The dogs 39, in the meantime will have passed over the upper end of 10 the head 36 and the shoulder 38 will have seated thereon. Said dogs will be thereby spread apart out of engagement with said shoulder and they, together with the tubing 40, may now be withdrawn.

15 The stem and bit are now rotated in the usual way, but the swivel 15, and the appendants thereof, may remain stationary. As the core is formed it passes up through 20 the opening 5 of the bit, and between the dogs 9 into the core barrel 13. A suitable fishing tool, of well known construction, may now be let down into the stem and engaged 25 with the shoulder 38. An upward pull will operate to carry the entire mechanism within the drill stem upwardly, the blades 31 being released from the lower end of the section 2 by the action of the pins 35 in the diverging bearings 34. At the same time 30 the upper ends of the push rods 11 will strike against the lower end of the nipple 3 and be forced downwardly and inwardly, forcing the dogs inwardly into engagement 35 with the core; and the entire device may then be pulled out from the drill stem, carrying the core with it.

What I claim is:—

1. A sample taking device, including a tubular stem, a core-forming bit attached thereto provided with a central passageway, 40 a core barrel within the stem, releasable means anchoring said barrel within said stem, separate core-engaging dogs depending from the barrel, said dogs being internally toothed, and aligned with said passageway, through which the core formed by said bit passes into said stem, and means for contracting said core-engaging dogs, and holding the same against the core during 45 the withdrawal of the barrel from said stem, said core engaging dogs and barrel being rotatable relative to the anchoring means.

2. A sample taking device, including a stem, a core-forming bit, provided with a central passageway, attached to said stem, and 50 adapted to be rotated by the stem, and formed with an annular groove, a core barrel within the stem and aligned above said

passageway and independently rotatable relative to the stem, releasable means anchoring said barrel within the stem, a downwardly converging anchor attached to the lower end of the core barrel whose lower end rests in said groove, core-engaging dogs depending from said barrel and between which the core passes from the bit into the barrel, 55 said dogs being located within said anchor and bearing against the converging walls thereof, and means for contracting said dogs against the core during the withdrawal of said barrel from the stem. 70

3. The combination with a tubular stem of a core-forming bit attached to the lower end thereof, provided with a central passageway and adapted to be rotated by the stem, a downwardly converging anchor within the 75 bit, core-engaging dogs located within the anchor in alignment with the passageway thereof and rotatable independently of the stem, releasable means to which said dogs are attached and by means of which they are anchored in position, said means being removable from said stem, and means for forcing said dogs downwardly in said anchor thereby contracting said dogs into engagement with said core, said contracting means 80 being actuated by the withdrawal of said anchoring means from the stem. 85

4. The combination with a tubular stem of a core-forming bit attached to the lower end thereof, provided with a central passageway, and an annular internal groove and 90 adapted to be rotated by the stem, releasable anchoring means adapted to be let down into and withdrawn from said stem, a swivel 95 depending from said means and independently rotatable with respect thereto, a core barrel depending from said swivel, a downwardly converging tubular anchor depending from the barrel and resting in said groove as a bearing, core-engaging dogs arranged within said anchor and between 100 which the core passes into said barrel, and means for forcing said dogs downwardly in the anchor thereby contracting them into engagement with said core, during the withdrawal of the barrel from the stem. 105

In testimony whereof I have signed my name to this specification in the presence of two subscribing witnesses.
